UNITED STATES PATENT OFFICE.

LOUIS A. NEMCOVSKY, OF NEW YORK, N. Y.

TYPEWRITING MACHINE.

Application filed December 19, 1922. Serial No. 607,766.

To all whom it may concern:

Be it known that I, LOUIS A. NEMCOVSKY, a citizen of the United States, and resident of New York city, in the county of New York and State of New York, have invented certain new and useful Improvements in Typewriting Machines, of which the following is a specification.

My present invention relates to typewriting mechanisms and has its more specific application to typewriters of the portable variety in which the parts of the mechanism are particularly light and compactly arranged to be conveniently carried in a small box or case.

In a preferred application, my typewriting machine comprises sub-assemblies easily put together to assemble the complete typewriter. In a preferred embodiment, the type levers, connecting linkage and type bars are mounted on a base frame. To the base frame is attached a sub-assembly comprising standards, a segment plate connected therebetween upon which the universal bar is mounted, said sub-assembly preferably carrying the ribbon spools and the automatic operating mechanism therefor. Preferably the ribbon spools are disposed at the sides of the machine in parallel planes and on studs protruding from the sub-assembly frame.

The invention is an improvement upon that of my copending application, Serial No. 589,571, filed Sept. 21, 1922.

In the accompanying drawings in which is shown, one of various possible embodiments of the several features of the invention,

Fig. 1 is a side elevation partly broken away of the assembled mechanism,

Fig. 2 is a plan view of the line spacing mechanism,

Fig. 3 is an end elevation, partly in section, of the line spacing mechanism set for single space,

Fig. 4 is a view similar to Fig. 3, showing the relation of the parts when operating,

Fig. 5 is a view similar to Figs. 3 and 4, showing the device set for double spacing,

Fig. 6 is a sectional view with parts broken away of one end of the ribbon reverse mechanism, taken along the line 6—6 of Fig. 1,

Fig. 7 is a plan view of the construction of Fig. 6,

Fig. 8 is a view similar to Fig. 7, on a larger scale, showing the ribbon advancing mechanism,

Fig. 9 is a plan view illustrating the ribbon mounting means,

Fig. 10 is a fragmentary view partly in section, illustrating the tabulating mechanism,

Fig. 11 is a transverse sectional view on an enlarged scale of the spool holder,

Fig. 12 is a sectional view taken along the line 12—12 of Fig. 11,

Fig. 13 is a sectional view taken along the line 13—13 of Fig. 11,

Fig. 14 is a view similar to Fig. 11 of a modified form of spool holder,

Fig. 15 is a plan view of the platen, illustrating the bell and margin release mechanism,

Fig. 15^a is a sectional view taken along the line 15^a—15^a of Fig. 15,

Fig. 16 is an end elevation thereof, and Fig. 17 is a detail view of the paper clip.

Similar reference characters refer to similar parts throughout the several views of the drawings.

The present application is a continuation in part and an improvement upon that disclosed in my copending application, Serial No. 589,571, filed September 21, 1922, in which the general arrangement of the parts of the machine are claimed. The claims herein are confined to the improved casing or frame structure, and to the associated ribbon reverse mechanism.

The line spacer mechanism, the ribbon shift mechanism and the bell and marginal release mechanism are claimed in my copending application, Serial No. 726,063, filed July 15, 1924.

Referring now to the drawings, I have shown a typewriting mechanism including a base frame 19 provided with a unitary stamped enclosure formed of enclosure side walls 20 and a top 21 said enclosure secured to said frame in the familiar manner as by screws not shown.

Within the base frame are supported the key levers 22, type bars 23, case shift mechanism 24 and other elements which need not be fully shown nor described in detail, as the same are fully set forth and claimed in my copending application above referred to, and taken alone are no part of the present invention. The base frame includes integral lateral lugs 25 for supporting there-

on a separate or secondary frame structure upon which are carried the ribbon spools and the ribbon reverse mechanism. In the preferred embodiment, the secondary frame structure comprises a pair of identical spool supporting standards 26 secured together in a unitary structure by the segment plate 27, which is connected at opposite ends to the standards, as by screws 28. The universal bar 42 is mounted on the segment plate in a manner not material to the invention claimed herein, but fully shown in my copending application above referred to. Each of the standards 26 includes an integral lateral spider 29 in a vertical plane, provided with a projecting horizontal spool holding stud 30 clamped in place by a nut 31, the latter contacting the ribbon feeding ratchet wheel 32 formed integral or rigid with the stud 30. The standards 26 are each provided with integral support lugs 33 superposed over the lugs 25 on the base and secured in place as by screws 34 to maintain the secondary frame structure in position.

The ribbon spools are thus lodged in vertical planes at the sides of the machine, and preferably in corresponding arcuate recesses 35 in the enclosure 20, as best shown in Fig. 1 of the drawings. The standards 26 are provided with cover plates 36 rigidly attached thereto and extending substantially flush with the top of cover 21, affording slits 37 for the ribbon 38, ribbon anchoring hooks 39 being provided on said cover plates for directing the ribbon to and from the frame 40 at which the type strikes. The ribbon is vibrated by mechanism shown in my copending application above referred to.

Ribbon reverse mechanism.

This mechanism is of the general type disclosed in my copending application above referred to, modified, however, for adaptation to the position of the ribbon spools in vertical rather than in horizontal planes. Each ratchet wheel 32 is operated through an associated pawl 41 actuated from the universal bar 42 for effecting the step by step advance. For this purpose, each of the pawls is provided with an integral lug, 43, pivoted as by screw 44 to a lug 45 integral with the universal bar 42, and maintained in coaction with ratchet wheel 31 by a coil spring 46 anchored to the universal bar lug 45. A detent pawl 47 is also provided for each ratchet wheel, pivoted as at 48 to the spider 29 and maintained in coaction with the ratchet wheel by a coil spring 50 anchored as at 51 to the spider frame, said detent pawl having a nose 52 extending over the corresponding actuating pawl 41. In the preferred embodiment, I employ a control bar 53 extending transversely across the machine and having a short slot 54 near

each end through which extends a fixed pin 55 to limit the displacement of the bar through a short range in the order of $\frac{1}{4}$ ", so that in one position, it will effect operative pawl connection for driving one of the spools, while the other is idle, and in the other position the driving relations will be reversed. The control bar is provided near each end with an integral cam tongue 56 which upon shift of the control bar toward the right from the position of Fig. 6 will pass under and raise the corresponding pawl 41 and the latter will raise detent pawl 47 to disconnect the driving transmission for the associated spool, the opposite pawls being concurrently disengaged by the corresponding cam tongue near the other end of the control bar, so that the associated springs will bring the latter pawls into driving relation with the opposite spool ratchet wheel.

Means is provided associated with the spools for determining the position of the control bar. This mechanism includes at each spool, a pivoted stud 57 mounting an arm 58 provided with a feeler roller 59 at its free end and pressed by the action of a coil spring 60 encircling stud 57 against the ribbon on the spool S. Movable with the stud 57 is a double arm element through which the reversing action is accomplished, when the ribbon on the associated spool reaches a predetermined diameter. In the path of arm 61 for actuation thereby is a bar shifting arm 62 pivoted as at 63 to the standard 26 and having a coil spring 64 thereabout, the free end of which presses against a stud 65 on the control bar 53, to shift the latter toward the right. In the path of an integral upstanding lug 66 on the other stud arm 67 is a locking pawl 68 having a tooth 69 pressed by a coil spring 70 against the edge of the control bar 53. The control bar has a locking notch 71 near each end into which tooth 69 of the corresponding locking pawl is automatically snapped by spring 70, when aligned therewith.

The operation will be readily understood by reference to Figs. 1, 6 and 7. The parts being in the relative position shown in Fig. 6, as the universal bar 42 moves forward upon striking of a key, the pawl 41 carried thereby, advances therewith and steps ratchet wheel 32, and with it spool S forward to click past detent pawl 47, which holds the ratchet wheel against return, while the pawl 41 returns with the universal bar and clicks over the ratchet wheel. The pawl and detent pawl for operating the opposite spool (not shown) are, of course, held in inoperative position by disengagement of the corresponding cam tongue (not shown) while spool S is being advanced, so that the ribbon is transferred,

as is readily understood, by a step by step movement from the right-hand to the left-hand spool. It will be noted that locking pawl 68 is out of alignment with the locking notch 71 at the left end, of course, in alignment at the right-hand spool. However, as the diameter of the ribbon on the right-hand spool decreases, the corresponding stud 57 is rotated by its coil spring 60 to maintain the feeler in contact therewith and to depress the corresponding arm 67, the lug 66 of which depresses the corresponding locking pawl 68 to free the control bar. As the ribbon is rolled upon spool S, the arm 58 is forced outward against the resistance of spring 60, rotating with it the stud 57 and the stud arms 61 and 67 about their common axis, until, when a predetermined diameter is reached, the arm 62 will be deflected by arm 61 to an extent sufficient to shift the control bar 53 through spring 64 until the locking pawl 68 snaps into notch 71 on the control bar. The cam tongue 56 in this shifting action passes under pawl 41 and raises it out of engagement with ratchet wheel 32, and said pawl, in turn, raises the detent pawl 47 out of operative engagement. The corresponding cam tongue at the right end of the control bar is currently disengaged from the right-hand pawl, so that the latter comes into engagement with the associated ratchet wheel.

Thus, in the continued operation, the reciprocation of the universal bar effects step by step advance of the right-hand spool, gathering the ribbon thereon from the left-hand spool, and as the latter approaches exhaustion, the descent of the cam 66 following the inward movement of the feeler arm 58, disengages pawl 68 from notch 71 to permit return shift of the control bar at the appropriate time. Preferably manually actuated release lever arms 72 are pivoted near the ends of the control bar, each retained by a coil spring 73 wound thereabout in elevated position away from the corresponding locking pawl 68 and each provided with a finger piece 74 through which it can be depressed to disengage the corresponding locking pawl, in order to permit reverse, or adjustment of the ribbon, by a manual action at any stage in the operation.

Spool holders.—In the preferred embodiment, special spool holders are provided by which the application and removal of the spools is rendered easy. One form of such holder is shown in Figs. 11, 12 and 13. In this form, stud 30 is bifurcated as at 75, a transverse pin 76 therethrough serving as a pivot for a locking arm 77 lodged within the bifurcation. A single turn of spring wire 78 rests in a peripheral groove 79 in the stud and extends about the tail end 80 of the locking arm, the end of said wire

being bent inwardly as at 81 and extending into the space between the legs of the stud. The tail end of the locking arm is reduced, as shown, so that the spring 78 in snugly engaging the bottom of groove 79 urges the nose 82 of the locking arm laterally into locking position, as shown. The locking lever nose has a beveled edge 83, so that as the hub 84 of the spool is slipped thereover upon the stud 30, the locking arm nose will automatically shift inward to the position shown in dotted lines in Fig. 11 and after the spool is completely in place, the spring 78 urges the locking lever outward to cause the nose 82 to overlap the face of the spool, thus retaining it in position against undesired removal. By simply shifting the locking arm manually to the dotted line position, the spool can be withdrawn by a direct pull thereon. The spool and stud are provided with the usual key connection or its equivalent to rotate in unison.

In the alternate form of spool locking element shown in Fig. 14, the locking arm is similarly pivoted in the stud, but instead of the coil spring, I here employ a leaf spring 78' fitting at one end 85 in a corresponding socket in the base of the stud and soldered at the other end in the tail 86 of the locking arm, the spring having a bias to urge the tongue toward the locking position.

Line spacer.

A preferred form of line spacer is shown in Figs. 1 to 5, and includes the usual ratchet wheel 87 upon the platen 88. The actuating mechanism therefor comprises an operating lever 89 preferably of sheet metal, having a handle or thumb-piece 90. A vertical axle pin 91 mounted in corresponding lugs 92 in the carriage frame, serves as the pivot axis for the lever 89, which is formed with integral lugs 93, through which the axle pin 91 passes. A spring 94 encircling the axle pin reacts at one end 95 against the carriage frame 96 and at the other against the arm 89 of the operating lever, thus, maintaining the latter normally in the outer position shown in Fig. 2. Projecting laterally from the arm is an integral rocker lug 93' fitting between the prongs of the forked end 97 of a transmitting lever 98, which is pivoted to the frame about a horizontal axis 99. The transmitting arm 98 has pivoted to the outer end thereof, a pawl 100 brought into permanent coaction with the ratchet wheel by a leaf spring 101 fixed at one end to the transmitting lever and reacting at its free end against an integral lug 102 projecting from the pivoted end of the pawl and normally pressed by said spring against the carriage frame. To determine the advance for single space or double space, as the case may be, I provide

a special stop for the transmitting lever 98 comprising a stop lever 103 pivoted near its middle, as at 104 and having a pin 105 extending into a notch 106 in the carriage frame, the projecting end 107 of the lever being readily accessible to the finger, for positioning it at either the extremity 108 of the notch, as shown in Fig. 4 or at the opposite extremity 109, as shown in Fig. 5. 10 In the former position, that is, the position shown in Fig. 4, the main length of the transmitting lever is limited, as shown in dotted lines, to a displacement corresponding to the rotation of the platen through the 15 width of a single line for single spacing. In Fig. 5, the stop lever 103 is shown at the opposite extremity of the notch, in which, it is aligned with a notch 110 near the end of the transmitting arm 98 to permit 20 displacement of the arm through a greater range for effecting rotation of the platen through the width of two lines for double spacing. To prevent over-running, I provide 25 a familiar form of detent for coaction with the ratchet wheel, said detent comprising a roller 111 mounted at the end of a stiff spring arm 112 and pressed thereby into coaction with teeth of the ratchet wheel. When it is desired to rotate the platen 30 through an angle greater than that corresponding to double spacing, the detent need merely be raised to inoperative position, whereupon the platen 88 can be freely turned. For this purpose, a special detent 35 holder arm 113 is provided, pivoted to the frame and having a notch 114 in its side for lodging the roller, as best shown in dotted lines in Fig. 5.

The operation of the line spacing mechanism will be apparent from the above description. It consists simply in deflecting the thumb piece 90 laterally in the direction of the arrow shown in Fig. 2, whereupon the rocker lug 96 on operating lever 89 will move the fork 97 on the transmitting lever 98 in counterclockwise direction to raise the transmitting lever with the pawl 100 to rotate the ratchet wheel 87 and with it the platen until the transmitting arm is 45 arrested by the stop lug 103, the range of displacement being through one space when the stop lug is set in the position shown in Fig. 4, in which it lies in the path of the main length of the transmission arm, while 50 55 when in the position shown in Fig. 5, the greater displacement for double spacing is permitted, as is apparent. When the thumb piece 90 is released, spring 94 returns the operating lever to the original position 60 shown in Fig. 2.

Paper clips, bell, carriage lock and marginal release.

Mounted on the carriage frame in pivots 65 115 for rotary adjustment about its longi-

tudinal axis is a rectangular bar 116. Near opposite ends of the bar are adjustably mounted identical paper clips preferably of simple sheet metal construction now to be described, held in coaction with the platen by the action of a coil spring 116' at one end of the bar. The clip at the right includes a sheet metal blank 117 bent, as shown in Fig. 17, including a pair of anchoring loops 118, snugly embracing the 70 rectangular bar 116 and an integral index pointer 119 to assist in positioning. Integral ears 120 are formed near the upper end of the clip to serve as supports for a roller 121, journaled therein to contact the 75 paper. The blank described, serves as a holder for a locking lever 122 pivoted thereon as at 123, and provided with an integral arm 124 having a tooth 125 thereon to fit into any of the succession of notches 126 80 in the bar, and retained therein by the pressure of a leaf spring 127 anchored at one end between one of the loops 118 and the bar 116, as shown in Fig. 15^a, and reacting against a lug 127' on the lever 122, to 85 maintain said lug against the upper edge of a slot 128 in the holder clip into which it projects. The locking lever also has an integral oblique projection 146 through 90 which the bell and margin lock element are actuated in a manner to be described below. A finger piece 129 is formed integral with the locking lever 122 and serves for depressing the tooth 125 out of engagement 95 with the notches 126 to permit release and shift of the clip 117 for positioning the same. The paper holding clip at the left is substantially identical with that described, the notches 120 on the bar at the left being, as usual, triangular to permit 100 ratcheting of the clip toward the right for clipping a narrow sheet, such as an envelope.

The bell 131 is of usual construction, but is preferably actuated through linkage of 105 special character now to be described. This linkage comprises a lever 132 formed as shown in the drawings, and pivoted as at 133 to a lug 134 on the frame and including a horizontal arm 135 to which is 110 pivoted an operating tooth 136 retained by a spring 137 in the position shown in the drawings, against the shoulder 138 on the lever. Pivoted to the lower end of lever 132 is the hammer element 139, a spring 140 anchored at one end to the hammer and at the other to the free end of the lever, serving to normally retain a lug 142 formed integral with the hammer, against the lever end 141. A coil spring 143 is anchored, 115 at one end to the frame and at the other to an integral lug 144 on lever 132, to maintain said lug in the position shown in the drawings, against shoulder 145 on the frame. As the platen moves toward the 120 125 130 135 140 145 150

left in normal operation, the operating lug 146 on the paper clip is brought into engagement with the pawl 136 and in the further movement thereof, shifts said pawl 5 and with it the lever 132 about pivot 133 as an axis against the resistance of spring 143 to elevate the hammer 139, until in the continued movement of the platen and with it of the paper clip, the pawl 136 is suddenly released, whereupon the spring 143 returns the lever 132 to its initial position, where it is sharply arrested by contact of lug 144 against shoulder 145. The hammer 139, however, continues its advance by inertia against the opposition of spring 140, after the lever 132 is thus arrested to strike bell 131 once, whereupon the spring 140 returns the hammer to the initial position shown in the drawings.

20 Pivoted to the frame bar 147 near the center thereof, is the carriage lock pawl 148, maintained in its normal inoperative setting by a leaf spring 149 extending lengthwise of edge 150 thereof. The carriage lock pawl has an upstanding oblique tooth 151 in the path of oblique lug 146 on the clip, so that as the latter is brought into engagement with said tooth in the approach of the carriage toward the end of 25 the line, it effects shifting of said lock pawl 148 against the resistance of spring 149, to urge tooth 151 into the notch 126 then aligned therewith, in order to lock the carriage against further advance. The carriage lock pawl 148 serves, moreover, to block the operation of the universal bar, so that the type bars cannot rise sufficiently to strike the platen, if a key be depressed when the carriage is thus locked. For this 30 purpose, I employ a lever 152 pivoted to the segment 27 as at 153 and having a lug 154 normally urged by a spring 155 toward a downwardly extending arm 156 on the carriage lock pawl 148, but arrested by contact with pin 155'. Lever 152 has a second lug 157 at its lower end normally to the side of a lug 158 formed integral with the universal bar 42. When the carriage lock pawl is in locking position, it will be seen 35 that the lever 152 is shifted by arm 156, lug 157 being thus brought immediately in front of lug 158, in the path of displacement of the universal bar, so that the latter cannot be displaced.

40 Thus, in the shift of the carriage, the actuating lug 146 on the clip first effects ringing of the bell and after continued movement of the carriage through a few additional spaces, the carriage lock pawl is actuated both to restrain the carriage against further displacement and to block the universal bar and consequently render the mechanism inoperative until the carriage has been returned toward the right.

45 In the return of the platen, spring 149 re-

stores the carriage lock pawl 148 to its inoperative position and spring 155 returns lever 152 to free the universal bar, as in Fig. 15. In the return movement of the platen, the operating lug 146 readily passes over 50 the pivoted tooth 136 on the bell actuating lever, which yields against the resistance of its holding spring 137, without effecting any substantial displacement of the lever 132, and, therefore, without ringing the bell. 55 The clip 117' at the left is similar to that at the right, except that the actuating tongue or lug 146' thereon is near the center thereof to engage hook or tooth 159 at the left end of the carriage lock pawl 148 and to urge said hook into a notch of the bar 116 to limit the return of the carriage.

60 To effect marginal release, after the carriage is locked, it is merely necessary to depress finger piece 160 on frame bar 147 65 which is pivoted at its ends as at 161. By this operation, carriage lock pawl 148 is disengaged from bar 116 and disposed out of the range of lever 152, so that the spring 155 will expand to release the universal bar. 70

In the preferred embodiment, the carriage 95 is advanced through a rack 162 carried thereby meshing with a pinion (not shown) on the carriage base plate 163, actuated through the escapement best shown in my copending application above referred to. The rack is supported by lever arms 164 pivoted to the carriage as at 165 and provided with a finger piece 166 upon depression of which the rack is elevated out of 100 engagement with the pinion to permit return of the carriage under the expansion of the usual drive spring (not shown). The usual adjustable tabulating stops 167 are provided on a longitudinally pivoted shaft 105 168 on the carriage frame, said shaft having mounted thereon a lug 169 for raising the rack 162. The tabulating stop is actuated through the usual tabulating key lever 170, which operates through pitman 171 to 110 shift arm 172 in the direction indicated by the arrow in Fig. 10. Arm 172 is rigid with shaft 168 to rotate the latter, for positioning the tabulating stop 167 in the path of the corresponding lug 173 on the movable carriage and substantially concurrently therewith elevating the rack 162 out of engagement with its associated pinion, so that the carriage will automatically move 115 under the expansion of the drive spring 120 until it is arrested by the tabulating stop.

To facilitate assembly, the arm 172 rigid with the shaft 168 is arranged to be readily attached to the pitman 171, after the carriage has been mounted upon the base. For 125 this purpose, I provide a pin 175 at the end of the arm 172 to be straddled by the hooked end 176 of pitman 171. For preventing undesired separation between pitman and arm, a coil spring 176 is provided, anchored upon 130

6
a screw 177 on the pitman, a loop 178 on said spring extending along the straddling face of hook 176, said loop having a restricted neck 179 past which the pin 175 is snapped into the loop, to effect the connection. The assembly of the device is effected, as will be apparent by mounting the carriage assembly upon the base in the manner described in my copending application 10 above referred to, mounting the frame structure, comprising the standards 26, segment plate 27 and ribbon mechanism, upon lugs 25 and securing it as already described, and effecting the connection of the tabulating mechanism, by simply straddling the hooked end of pitman 171 over pin 175 on arm 172 and applying pressure to snap the spring loop 178 into locking position.

It will be noted that I have thus provided 20 a typewriting mechanism of simple, light and compact construction, which can be readily assembled and which performs substantially all of the operations of an ordinary typewriter of larger, heavier and more 25 complex construction. The mechanism has a standard keyboard and includes automatic ribbon shift and ribbon reversing mechanism, as well as adjustable line spacing mechanism, a bell, marginal release and tabulating mechanism. In operation all of the 30 parts are readily and conveniently accessible, the ribbon spools being in inobtrusive, yet readily accessible position in the side of the frame, and the line spacing operating thumb piece projects laterally of the platen for ready and convenient access.

Although the frame 19 and the auxiliary frame structure including standards 26, may be cast metal, and the enclosure 20, 21, 36 40 of stamped metal, it is preferred to form all of these elements of fibre or wood impregnated with phenol condensation product or the like, according to known processes, which renders the product durable and prevents distortion or destruction under heat, moisture, and the usual mechanical impact incurred in typewriting machines. With the fibrous elements set forth, the machine is rendered more silent in operation, in that, 45 the structural supports will damp the vibrations of the mechanism, and the fibrous enclosure will eliminate the sound board amplifying effect, sometimes inherent in metal enclosed typewriting machines.

50 It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this inven-

tion could be made without departing from the scope thereof, it is intended that all matter contained in the above description or shown in the accompanying drawings shall be interpreted as illustrative and not in a limiting sense.

Having thus described my invention, what I claim as new and desire to secure by Letters-Patent of the United States is:

1. In a typewriting machine, in combination, a base frame, a separable frame comprising a pair of standards and a segment plate secured to and connecting said standards, each of said standards having ribbon spool mounting means thereon, and means securing said standards upon said base frame.

2. In a typewriting machine, in combination, a base frame, a separable frame comprising a pair of standards, a segment plate connecting said standards into a unitary structure, horizontal axles projecting from the ends of said structure to sustain ribbon spools with the faces thereof in vertical planes, said base frame having support means near the opposite ends thereof for sustaining the standards of said structure, and means detachably securing said standards to said base frame.

3. In a typewriting machine, in combination, a base frame, a separable frame comprising a pair of standards and a segment plate secured to and connecting said standards into a unitary structure, each of said standards having ribbon spool mounting means thereon, means securing said standards upon said base frame, and automatic ribbon reversing mechanism carried by said structure.

4. In a typewriting machine, in combination, a base frame, a separable frame comprising a pair of standards and a segment plate connecting said standards into a unitary structure, horizontal supporting axles projecting from the ends of said structure to sustain ribbon spools with the faces thereof in vertical planes, said base frame having support means near the opposite ends thereof for sustaining the standards of said structure, means detachably securing said standards to said base frame, ribbon reversing mechanism carried by said structure, said mechanism including a control bar extending transversely across the width of said structure, and operating mechanism controlled by the diameter of ribbon on the spool for effecting shift thereof.

5. In a typewriting machine, in combination, a base frame, a frame structure detachably mounted thereon, a cover having side walls, and axles on said frame structure near opposite ends thereof and at right angles to said side walls for releasably mounting the ribbon spools with the faces

thereof substantially in the planes of said side walls whereby said spools are readily accessible for removal from said axles.

6. In a typewriting machine, in combination, a base frame, a cover therefor having side walls, a frame structure detachably mounted upon said base frame, said structure having horizontal support axles near the opposite ends thereof for ribbon spools, 10 said side walls being cut away for accommodating the ribbon spools substantially flush therewith.

7. In a typewriting machine, in combination, a base frame, a separable frame structure mounted thereon and including a segment plate, and a universal bar associated with said segment plate, said frame structure having ribbon spool mounting means thereon.

20 8. In a typewriting machine, in combination, a base frame, a frame structure detachably mounted thereon, said frame structure extending transversely across the machine and having supports for sustaining 25 ribbon spools with their faces in substantially vertical planes, cover means for said typewriter having side walls substantially in the planes of the spool faces, said separable frame structure having a cover portion complementary to the top of said cover affording passages for the ribbon to and from the spools, and guide hooks for the ribbon carried by said structure.

9. In a typewriting machine, in combination, a base frame, a pair of standards, a segment plate connecting said standards into a unitary separable frame structure, means detachably securing said frame structure upon said base frame, each of said standards 40 having a horizontal axle thereon for a ribbon spool, a cover for said typewriter, said standards having cover extensions complementary to the top of said cover affording slits for the passage of the typewriter ribbon, 45 guide hooks on said cover extensions to direct the ribbon into the path of the type, and automatic ribbon reversing mechanism carried by said structure.

10. In a typewriting machine, in combination, a separable frame structure comprising 50 a pair of identical standards, a segment plate connecting said standards, ribbon spool support axles extending horizontally from opposite ends of said frame structure, and 55 guide hooks on said standards for directing the ribbon in operation.

11. A ribbon reverse mechanism comprising in combination, a pair of spools, a universal bar, pawls connected to said bar, 60 ratchet wheels coaxial with said spools for coaction with said pawls, a control bar extending across the machine and coacting

with said pawls to dispose either out of operative coaction with the corresponding ratchet wheel, means to concurrently retain 65 the other pawl in operative position, means associated with each spool for connecting it to the control bar to shift the latter for ribbon reverse when the feed spool reaches a predetermined diameter of ribbon, said 70 means comprising a pivoted feeler member contacting the outer convolution of ribbon being wound, a pivot post for said feeler member, a shift member actuated from said pivot post when said feeler member reaches 75 a predetermined position as the diameter of the ribbon spool increases, said shift member coacting with said control member to urge the same for ribbon reverse, and a lock lever controlled from said pivot post to lock 80 the control bar in fixed position for the reverse operation.

12. In a typewriting mechanism, in combination, a pair of ribbon spools in parallel vertical planes operating pawls therefor, 85 automatic reversing actuating means therefor comprising a control bar, extending transversely of the mechanism between said pawls at right angles to said spools, ribbon advancing pawls interlocked by said control 90 bar, so that only one is in operative position at a time, locking pawls near opposite ends of said frame for coaction with said control bar, shifting arms near opposite ends of said frame for actuating the control bar, control 95 arms associated with said ribbon spools and pivoted parallel to the axis thereof and controlled by the thickness of ribbon thereon, each of said control arms coacting with the corresponding locking pawl and shifting 100 arm.

13. In a ribbon reverse mechanism, in combination, a control bar, a locking lever coacting with a notch therein, a releasing lever pivoted to said control bar, spring 105 means urging said releasing lever out of coaction with said locking lever, said releasing lever having a finger piece by which it may be displaced about its pivot against the resistance of said spring to release said locking 110 lever from coaction with the notch in said control bar.

14. In a spool holder, in combination, a bifurcated axle stud, a locking lever extending longitudinally between the legs of the 115 stud and pivoted therein, and a spring ring encircling the stud and fitting into a circumferential groove therein and having a lug extending between the legs of the stud.

Signed at New York, in the county of 120 New York and State of New York, this 18th day of December, A. D. 1922.

LOUIS A. NEMCOVSKY,
